PACKAGING DEVICE

Filed March 15, 1930

UNITED STATES PATENT OFFICE

CARL W. AEPPLER AND LESLIE LAWRENCE, OF OCONOMOWOC, WISCONSIN

PACKAGING DEVICE

Application filed March 15, 1930. Serial No. 436,213.

This invention pertains to a packaging device, and while the same may be applied to the wrapping or covering of various articles, it is particularly designed for use in connection with comb honey, which because of its fragile character, must be handled with extreme care.

At the present time, numerous articles, such as honey, molded cracker jack, confections, and the like, are usually placed in cartons or wrapped with a suitable paper covering folded over upon the ends.

Both are expensive, and the latter method requires considerable time and awkward and difficult operations. This is particularly true where it is attempted to wrap comb honey, as the average honey producer does not pack sufficient combs to warrant the installation of expensive wrapping machinery, if such there be, and must therefore perform the wrapping operation manually.

To overcome the foregoing objections and provide suitable covering for articles, such as comb honey and the like, the present invention contemplates the use of paper bags, which may be of any conventional structure, or provided with transparent sides or windows to render the article visible. In either instance, it will be appreciated that considerable difficulty is encountered in opening a folded paper bag sufficiently to permit insertion of the article without damage to the article or bag.

The present invention has primarily for its object the provision of a simple, inexpensive device adapted to facilitate the proper opening for a paper bag and the insertion of an article thereinto without damage to either, and in such manner as to obtain a neat and highly attractive package.

Incidental to the foregoing, a more specific object resides in the provision of a device comprising a pair of spaced blades for receiving and gradually opening a folded paper bag, as the same is forced thereover, said blades being yieldable with relation to each other to facilitate initial insertion into the open end of the bag, and one of said blades being provided with means for guiding an article into the expanded or open bag.

A more specific object of the present invention resides in the provision of a device of the foregoing character in which one of the blades is substantially rigid and provided with guides adjacent its longitudinal edges, while the other blade is yieldable with relation thereto, so that the ends of the blades may be contracted for initial insertion into the end of the bag. 55

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims. 60

In the accompanying drawings is illustrated one complete example of the physical embodiment of the present invention constructed according to the best mode so far devised for the practical application of the principles thereof. 70

In the drawings, Figure 1 is a front elevation;

Figure 2 is a plan elevation;

Figure 3 is a fragmentary front elevation illustrating the initial insertion of the blades 80 into the end of a bag; and

Figure 4 is an end elevation with the bag positioned upon the spreading blades, and shown in section.

Referring now more particularly to the accompanying drawings, that form of the invention illustrated comprises a base designated by the numeral 1, and provided with countersunk screw holes to permit the same to be permanently fastened to any suitable support. 85

Fastened upon the base adjacent its front edge is a spreading blade 3, one end of which projects beyond the base and terminates in a rounded nose 4 to facilitate insertion into the end of a folded paper bag. The longitudinal edges of the blade 3 are turned upwardly to provide front and rear guides 5 and 6, respectively, the rear guides 6 extending throughout the major portion of the blade 95

3, while the front guide terminates intermediate the ends of the blade to facilitate placing of an article upon the blade from the front of the device and aligning the same with the rear guard 6 prior to sliding the article along the blade for insertion into a bag, as will be hereinafter more fully described.

Spaced above the base 1 and mounted upon the post 7 is a support 8 having secured to its underface a second spreading blade 9, which is aligned longitudinally and vertically with the lower blade 3, and extends beyond the support a corresponding distance to the extension of the blade 3 beyond the base 1. The blade 9 is preferably formed of resilient material to permit contraction of its outer end with relation to the outer end of the blade 3 for the purpose to be described in connection with the operation of the device.

While the base and support 8 are illustrated as formed from wood, it will be understood that various structures are contemplated, it being merely essential to the operation of the present invention that the spreading blades 3 and 9 be positioned in spaced relation to each other and relatively yieldable.

Taking up the operation of the present device, reference will be had to Figure 3, which illustrates the initial operation of depressing the top blade 9 to cause its outer end to be contracted with relation to the end of the lower blade 3, after which operation the ends of the blades are inserted into the mouth of a paper bag. The bag, which is initially folded, can then readily be threaded or slid over the blades, during which operation the same will be opened, as shown in Figures 1 and 4, it being understood that the blades 9 and 3 are of substantially the same width as the bag. After the bag has been strung upon the spreading blades, the article A, which may represent a comb of honey or like object, is placed upon that end of the blade 3 secured to the base against the rear guide 6.

The article is then manually slid forwardly upon the blade 3 and guided into the open end of the bag by the guides 5 and 6. When the forward end of the article engages the closed end of the bag, further movement serves to strip the bag from the spreader blades, after which the open end may be folded over and glued, or otherwise secured, to form a complete covering for the article.

The operation is then repeated, and it will be obvious that little practice will be required to enable an operator to become highly skilled in the necessary operations, which by means of the present invention are materially facilitated and enable an operator to rapidly insert articles into bags without damage to either the bags or articles.

I claim:

1. A device of the character described comprising a base, a blade secured thereto and projecting beyond said base, a support positioned above said base, a second blade carried by said support and aligned longitudinally and vertically with said first mentioned blade and cooperating with said first mentioned blade for receiving and spreading a folded paper bag, and means carried by said first mentioned blade for guiding an article into the bag. 70

2. A device of the character described comprising a pair of spaced blades relatively yieldable for receiving and spreading a folded paper bag, and guides carried by one of said blades adjacent its longitudinal edges, one of said guides terminating short of the other to permit an article to be slid upon said blade from the front and against the other of said guides. 80

In testimony that we claim the foregoing we have hereunto set our hands at Oconomowoc, in the county of Waukesha and State of Wisconsin.

CARL W. AEPPLER.
LESLIE LAWRENCE.
